US00D956251S

(12) United States Design Patent (10) Patent No.: US D956,251 S
Marton et al. (45) Date of Patent:  *Jun. 28, 2022

- (54) PERCUSSIVE MASSAGE DEVICE
- (71) Applicant: Hyper Ice, Inc., Irvine, CA (US)
- (72) Inventors: Robert Marton, Yorba Linda, CA (US); Anthony Katz, Laguna Niguel, CA (US)
- (73) Assignee: Hyper Ice, Inc., Irvine, CA (US)
- (*) Notice: This patent is subject to a terminal disclaimer.
- () Term: 15 Years
- (21) Appl. No.: 29/744,887
- (22) Filed: Jul. 31, 2020
- (51) LOC (13) Cl. 28-03
- (52) U.S. Cl. USPC D24/215
- (58) Field of Classification Search
USPC D24/200, 211, 212, 213, 214, 215; D8/14.1; D28/13
CPC . A61H 2201/1653; A61H 23/006; A61H 1/00

(57) CLAIM

The ornamental design for a "percussive massage device," as shown and described.

DESCRIPTION

FIG. 1 is a front perspective view of a percussive massage device, showing our new design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines in the drawings are for the purposes of illustrating portions of the percussive massage device, which form no part of the claimed design.

1 Claim, 6 Drawing Sheets
